US0D1061528S

(12) **United States Design Patent** (10) Patent No.: **US D1,061,528 S**
(45) Date of Patent: ** Feb. 11, 2025

(54) **HOUSING PLATE**(71) Applicant: **Apple Inc.**, Cupertino, CA (US)(72) Inventors: **Richard Hung Minh Dinh**, Saratoga, CA (US); **Richard P. Howarth**, San Francisco, CA (US); **Scott A. Myers**, San Francisco, CA (US); **David A. Pakula**, San Francisco, CA (US); **Tang Yew Tan**, San Francisco, CA (US)(73) Assignee: **Apple Inc.**, Cupertino, CA (US)(**) Term: **15 Years**(21) Appl. No.: **29/821,033**(22) Filed: **Dec. 27, 2021****Related U.S. Application Data**

(60) Continuation of application No. 29/658,273, filed on Jul. 30, 2018, now Pat. No. Des. 939,509, which is a continuation of application No. 29/554,625, filed on Feb. 12, 2016, now Pat. No. Des. 824,389, which is a continuation of application No. 29/503,544, filed on Sep. 26, 2014, now Pat. No. Des. 749,590, which is a continuation of application No. 29/429,885, filed on Aug. 17, 2012, now Pat. No. Des. 714,294, said application No. 29/554,625 is a continuation of application No. 13/561,567, filed on Jul. 30, 2012, now Pat. No. 9,867,301, said application No. 29/429,885 is a continuation of application No. 29/363,173, filed on Jun. 5, 2010, now Pat. No. Des. 666,202, said application No. 13/561,567 is a division of application No. 12/794,467, filed on Jun. 4, 2010, now Pat. No. 8,264,837.
